UNITED STATES PATENT OFFICE.

GEORGE H. NORDRUM, OF ST. PAUL, MINNESOTA, ASSIGNOR OF ONE-THIRD TO HENRY G. NORDRUM AND ONE-THIRD TO J. W. HAMILTON, BOTH OF ST. PAUL, MINNESOTA.

ATTACHMENT FOR WRITING INSTRUMENTS.

Application filed February 10, 1928. Serial No. 253,293.

As is well known, writing with a pen or pencil for long periods of time often results in painful strain or even temporary paralysis of the writer's forearm or wrist. It is the object of this invention to relieve such strain or paralysis by providing resiliently supported rests for those fingers of the writer which grip the writing instrument.

More particularly it is my object to provide an attachment with rests for the forefinger and thumb of the writer supported upon metallic leaf springs which normally project obliquely from the shaft of the instrument together with means for quickly and easily retracting said rests when the device is not in use. Another object is to provide a device of this kind adapted to be quickly and easily attached to a writing instrument of common form.

The invention will be best understood by reference to the accompanying drawings in which Figure 1 is a side elevation of my device attached to a pencil of common type and with the finger rests in extended position; Fig. 2 is a plan view of the same; Fig. 3 is an enlarged section taken on the line 3—3 of Fig. 1 and with the rests retracted and Fig. 4 is an enlarged section taken on the line 4—4 of Fig. 1.

As shown in the drawings, where the device is to be attached to pencils of the more or less standard type I provide a sleeve 5 adapted to fit upon and encase the shaft 6 of the pencil. Secured to one side of the sleeve 5 is a leaf spring 7 which normally projects obliquely downward therefrom. Upon the movable end of this spring 7 is a rest 8 for the forefinger of the writer. This rest is preferably formed with a depression to retain the finger in place thereon and an outwardly bent flange 9 to prevent the finger from sliding off the end of the rest. Registering with the rest 8 in the side of the sleeve 5 is an opening 10 into which the rest is retracted when not in use. Another rest 11 for the thumb of the writer is provided on the side of the sleeve 5. This rest 11 is also resiliently supported so as to project from the side of the sleeve upon an oblique spring 12. An opening 13 in the sleeve 5 is arranged to register with the rest 11 to receive the same when it is retracted as hereinafter described.

To retain the sleeve 5 upon the shaft 6 when the attachment is in use, I provide a pair of dogs 14. These dogs normally project from

opposite sides of the sleeve 5 and are arranged to be pressed inward upon the pencil shaft 6 through openings 15 in the sleeve. The dogs 14 in the embodiment shown are formed integral with the sleeve 5 at the lower end of the openings 15 as clearly shown in Fig. 1. Slidable longitudinally on the sleeve is a ring 16 adapted to be moved to the right from the position shown in Fig. 1 to press the dogs 14 inward through the opening 15 and against the shaft 6. This ring 16 is also movable toward the left from the position shown in Fig. 1 to the dotted line position where it retains the rests 8 and 11 in retracted position. When in retracted position the rests 8 and 11 project through the openings 10 and 14 respectively into engagement with the shaft 6 and thereby retain the sleeve 5 in place. A stop 17 projects from the sleeve 5 to limit movement of the ring 16 in one direction and a small projection 18 limits movement in the other direction.

The operation of the device will now be readily understood. To attach the device to the pencil the sleeve 5 is merely slipped over the shaft 6 to the desired position and then the ring 16 is drawn over the dogs 14 into engagement with the stop 17. This presses the dogs 14 into gripping engagement with the shaft 6 and retains the sleeve thereon. Now the writer places the forefinger (or second finger) on the rest 8 and thumb on the rest 11 so that a resilient grip is established. I have found that this device greatly relieves muscle strain and facilitates writing for long periods of time.

When the pen or pencil is not in use the ring 16 is moved to the dotted line position indicated in Fig. 1. This confines the rests 8 and 11 to compact position against the shaft 6 of the instrument and at the same time retains the sleeve 5 in place by pressing the rests 8 and 11 into firm frictional contact with the shaft 6. When so retracted the rests offer no obstruction to inserting the instrument in a pocket or other receptacle.

It will be evident that the springs 7 and 12 may be attached directly to the pen or pencil shaft and numerous other modifications are considered to be within the spirit of my invention.

Having described my invention what I claim is new and desire to protect by Letters Patent is:

1. An attachment for a writing instrument

having a shaft comprising a sleeve adapted to receive said shaft, finger rests normally projecting from the sides of said sleeve, resilient supports for said rests adapted to normally maintain the same in extended position, means for securing said sleeve on said shaft and means for retracting said rests against the action of said supports.

2. An attachment for a writing instrument having a shaft comprising a resilient support projecting obliquely downward from the side of said shaft, a rest supported on the outer end of said resilient support, a second shorter resilient support projecting obliquely from the side of said shaft, a thumb rest carried on said second spring and a ring slideable along said shaft and movable from a position clear of the upper ends of said supports to a position overlapping and confining said supports closely adjacent to said shaft to retract said rests against the sides of said shaft.

3. An attachment for a writing instrument having a shaft comprising a sleeve adapted to receive said shaft, finger rests normally projecting obliquely downward from the sides of said sleeve and permanently secured thereto at their upper ends, resilient supports for said rests adapted to normally maintain the same in extended position, means for securing said sleeve on said shaft and a ring slideable along said sleeve from a position clear of said supports to another position overlapping said supports for retracting said rests against the action of said supports.

4. An attachment for a writing instrument having a shaft, comprising a sleeve adapted to receive said shaft, finger rests normally projecting in spaced relation to the sides of

said sleeve, resilient supports for said rests permanently secured to said sleeve and projecting obliquely therefrom to normally maintain said rests in extended position, said sleeve being formed with an opening, a dog secured to said sleeve and arranged to be extended inward through said opening to engage said shaft, and a ring slideable along said sleeve and adapted in one position to confine said dog in engagement with said shaft for securing said sleeve thereon and adapted in another position to confine said rests closely adjacent to the sleeve.

5. An attachment for a writing instrument having a shaft, comprising a sleeve adapted to receive said shaft, finger rests normally projecting in spaced relation to the sides of said sleeve, resilient supports for said rests permanently secured to said sleeve and projecting obliquely therefrom to normally maintain said rests in extended position, said sleeve being formed with an opening, a dog secured to said sleeve and arranged to be extended inward through said opening to engage said shaft, said sleeve having a second opening arranged to receive one of said rests when in retracted position and a ring slideable along said sleeve and adapted in one position to confine said dog in engagement with said shaft for securing said sleeve thereon and adapted in another position to confine said rests closely adjacent to the sleeve and to extend one of said rests into frictional engagement with the shaft through said second opening.

In testimony whereof, I have hereunto signed my name to this specification.

GEORGE H. NORDRUM.
